DISPENSING DEVICE

Phillip M. Chernoff, Middletown, Conn.

Application January 22, 1937, Serial No. 121,881

4 Claims. (Cl. 221—62)

My present invention, in its broad aspect, has to do with containers and dispensers for use with powdery substances such as tooth powder, salt, soap, sugar, and any other type of powdery substance which may be carried in a container and dispensed when desired for use. More particularly it is my purpose to provide a cheap, simple and convenient device for storing and dispensing powdery or granular material such as tooth powder, sodium perborate, or salt, or other substance to promote their use in mouth hygiene, and which may be attached to a wall or any upright base. Essentially my invention consists of five parts (1) a container for the substance, (2) a dispensing device, (3) means for guiding and retaining a toothbrush or the like in proper position, (4) a wall attachment, and (5) means for catching excess powder falling on the brush.

Among the principal advantages of my invention are briefly defined the following; first the powdery or granular substance such as toothpowder or sodium perborate powder, or salt or the like, is retained in the container in a clean, dry condition; second, my dispensing device includes in addition to a valved opening in the bottom of the container, a pusher and agitator so that action is positive, certain, and the amount released on pushing the valve more or less determined; third, my device is formed of sheet metal, more or less in the nature of a stamping, which can be quickly and cheaply manufactured and artistically decorated, and sold at small cost and there are no parts to get out of order, or which might become dirty or unclean, or catch the clothing or clog the device; fourth, the means for positioning the brush or the like is certain and simple in construction and the brush is automatically guided to proper position for receiving its charge of powder, and fifth, excess powder is not lost or dropped to the floor but caught in a special attachment below the dispensing valve.

Other and equally important objects and advantages will be apparent as the description proceeds, but attention is called to the fact that in the forms here shown right is reserved to make such changes in construction, form, shape and position of parts as are within the scope of my inventive concept, and within the definition thereof contained in the appended claims.

In the drawing wherein a principal form and a modification of my dispensing device are shown:—

Figure 1 is a sectional side elevation;

Figure 2 is a detail view,

Figure 3 is a perspective view of the pusher and valve,

Figure 4 is a perspective view of the guides and trough, and

Figure 5 is a sectional side view of a modified form of my invention.

In the drawing wherein like characters of reference are used to designate like or similar parts throughout the several views thereof:—

The numeral (1) designates preferably a cylindrical or oval (or it may be any other shape) sheet metal container having sides (2), a bottom (3) and a removable top (4). An attachment (5) at the back of the container is designed to mount the same on a nail, screw or hook in a vertical base or a wall or the like. The bottom (3) of the container has an elongated slot (6) therein so that powdery or granular material (not shown) in the container may pass out the bottom. The under surface of the bottom carries a frame (7) which may be soldered or riveted thereto (see Figure 4) and which is provided with a raised part (8) having end pieces (9) constituting guides, and a center piece (10) formed with an opening (11) about which is a rectangular guard (11a) having an elongated, underbent side (12) forming a trough for receiving surplus powder. At the rear of the frame (7) is a support (13) for a spring (14), the other end of which is received in a similar support (15) carried on the slide member (16).

The slide member (16) works back and forth in the guides (9) when the device is assembled and has a slot (17) registering with the slot (6) and opening (11) when material is to be dispensed from container (1) and out of registry therewith when the container is to be closed. The slide is normally held closed by the force of spring (14). A finger piece (18) is provided for pushing the guide, and adjacent the slot (17) are formed upstanding curved arms (19) terminating in a vertically arranged, downwardly extending plate (20) which functions as a plow or pusher since the arms (19) and plate (20) extend through the slot (6) into the container and come into contact with the material therein. The upper edge of plate (20) is provided with teeth (21) which serve as agitators. The closed position of my device is illustrated in Figure 1, and the open position in Figure 2, and in connection therewith it will be noted that when the slide (16) is pushed to open up the slot (6) the plate passes across the slot (6) and pushes material through it and down into the guard and upon a brush or the like disposed therebeneath.

The elongated side of the guard serves two purposes (1) as a guide for the brush, and (2) as a supporting member for the trough member (22) formed by the underbent portion of the elongated side (12), so that surplus powder is caught and preserved for further use.

In Figure 5, I have illustrated a simplified modified form of my device wherein an ordinary slide valve (23) is used in the interior of the container, 10 and which is retained in guides (24) and has a slot (25) registering with slot (6) and a finger button or grip extending outside the container and indicated by the numeral (26). The finger piece (26) is pulled in the direction of the arrow 15 to open the device, and outwardly flared flange pieces on the bottom of the container serve as guides and positioners for the brush, the flange pieces being indicated by the numeral (27) and the brush by the letter (A). In operation the 20 brush (A) is simply placed between the guides or flange pieces (27) and the valve pulled to release the powder from the container.

It is believed that the operation of my device is apparent from the foregoing, but emphasis is 25 again made of the right to make such changes as may be indicated by different conditions of practice, provided same fall within the scope of the appended claims.

I claim:—

30 1. A dispensing device comprising a container, a valve device for controlling delivery of the contents from the container, said container being provided with an outlet opening; said valve device having a frame formed with guide members 35 and a guard arranged to register with the outlet opening, a slide member moving in the guides and having an opening designed to register with the outlet opening and a closure portion arranged to close said outlet opening, a spring member arranged between the frame and the slide member 40 for normally holding the slide member in closing position, the guard member having an elongated side forming a guide, and bent at its free end to form a trough for catching excess or spilled material from the container.

45 2. A dispensing device comprising a container, and a valve device for controlling delivery of the

contents from the container, said container being provided with an outlet opening; said valve device having a frame with spaced guide members and a four sided guard arranged to register with the outlet opening, a slide member moving in the guides and having an opening designed to register with the outlet opening and a closure portion arranged to close said outlet opening, a resilient member 5 arranged between the frame and the slide member for normally holding the slide member in closing position, a side of the guard member being extended to form a guide, and bent at its free end to provide a trough for catching excess or spilled material from the container.

3. A dispensing device comprising a container, 10 said container provided with an outlet opening, a valve device for controlling egress of the contents of the container through the outlet opening, a frame carried by the container adjacent the outlet, a nozzle-like guard member on the frame 20 spaced from and beneath the outlet opening to receive the dispensed contents of the container therethrough, said frame having spaced flanged portions, a spring controlled valve device supported on the flanges of the frame between the guard 25 and the outlet opening, and a part of the material of the guard being extended downwardly and bent to form a trough to catch excess or spilled material from the container.

4. A dispensing device comprising a container 30 provided with an outlet opening, a frame carried by the container, a slide valve carried by the frame for controlling egress of the contents of the container through the outlet opening, said valve having a pair of upstruck arms extending vertically through the outlet opening and similarly bent at their upper ends, and a plate-like depending pusher carried by the bent upper ends of the arms and extending downwardly therefrom in spaced relationship to the arms to a point in 40 proximity with the bottom of the container, the upper edge of said pusher having teeth to agitate the contents of the container when the valve is moved, and a resilient device for controlling the opening and closing of said valve. 45

PHILLIP M. CHERNOFF.
